TELEPHONE-EXCHANGE SYSTEM.

1,109,703.

Specification of Letters Patent. Patented Sept. 8, 1914.

Application filed March 20, 1912. Serial No. 684,946.

To all whom it may concern:

Be it known that I, FRANK N. REEVES, a citizen of the United States, residing at New York, in the county of New York and State 5 of New York, have invented a certain new and useful Improvement in Telephone-Exchange Systems, of which the following is a full, clear, concise, and exact description.

This invention relates to telephone exchange systems of the type in which automatic switches or selectors are employed for the interconnection of telephone lines, and it has for its object in general, to provide improved means associated with the switch 10 mechanisms thereof for governing their operation.

According to a well-known method of operation in automatic and semi-automatic telephone exchange systems, a series of selector 15 switch mechanisms are arranged and controlled to operate successively in making any desired connection, each of said switch mechanisms, by means of suitable controlling apparatus, being caused first to associate itself 20 with a particular one of a plurality of groups of lines and then to operate automatically to find and make connection to an idle line of that group. These lines may be trunks adapted to form intermediate connections 25 between the subscribers lines, or they may be a group of subscribers lines extending to a single substation, such as a private branch exchange. They are ordinarily connected to multiple terminals of a plurality 30 of selectors.

There is usually associated with each selector a device known as a sequence switch the function of which is to establish in a definite order at successive stages the various 35 circuits required to control the operation of the selector. Such a device is illustrated in United States patent to McBerty No. 1,009,080 dated November 21, 1911. It is usual in such systems for the purpose of establishing partially completed connections 40 to provide a device known as a wipe-out key, which, when depressed, operates to restore the apparatus to normal position without establishing the connection initiated.

The present invention relates more particularly to means associated with such selectors to govern their operation in finding and making connection to idle lines, although it 45 may be applied, if desired, to the control of

selectors for performing other operations 55 than that of connecting lines.

It is one of the objects of this invention to cause the selector as well as the sequence switch to be invariably restored to its normal position when the wipe-out key is operated, in other words, to prevent a complete sequence of operations of the sequence switch without a complete restorative movement of the selector under control. To this end, an electrical interlocking arrangement 60 between the sequence switch and selector is provided rendered active by the actuation of the wipe-out key, whereby only through circuits closed alternately by each other may the sequence switch and selector be restored. 65

Another feature of this invention is directed to the provision of means for preventing the selector from testing the trunks which appear upon it in case the wipe-out key is actuated prior to the movement of the brush carriage or during its travel, that is to say, for preventing in such event the movement of the brush carriage from being arrested by its test brush engaging an idle trunk in its travel, this resulting in a saving of time. In accordance with this feature of the invention, upon the operation of the wipe-out key electromagnetic means is provided adapted to cause the test circuit to be opened, and the selector and sequence switch 85 to be restored.

A third feature of the invention relates to the provision of means for preventing interference with existing calls. In the system of this invention, an idle trunk is one upon the 90 test terminal of which a certain electrical condition exists, and a busy trunk one upon the test terminal of which a different electrical condition exists, a test relay operating to seize the trunk or not, according to the 95 electrical condition of its test terminal. Upon seizing an idle trunk, this test relay brings about a change in the electrical condition of its test terminal to cause it to test busy to other selectors, and it is essential 100 that this changed condition be maintained from the time the trunk which it represents is seized until it is released. To this end, means is provided for causing the immediate disestablishment of the call in the event this 105 change in the electrical condition is not so maintained. A suitable signal may be provided to inform the operator of this, or the

calling subscriber himself may bring it to her attention. In the present system, the idle condition of a trunk is indicated by a certain potential of the test terminal to 5 which the test relay is responsive and the busy condition by a lower potential to which the test relay is unresponsive. The test relay may have two windings, one of high resistance included in circuit during the test 10 operation and one of low resistance included in circuit in shunt of the high resistance path when connection is made with an idle trunk to reduce the potential upon its test terminal to cause it to test busy to other 15 selectors. The motor magnet which actuates the selector may be excited by the deenergization of a relay in this low resistance circuit so that in case the low resistance path is subsequently opened during the pendency 20 of a conversation, the circuit of the selector motor magnet is closed which restores the selector and its associated sequence switch to normal position.

Still another feature of the system concerns the reduction of errors on the part of the automatic switching mechanism in setting up calls, and the prevention of interference with existing calls. In power-driven selectors wherein the power is cut off 25 from the selector when the test brush encounters a test terminal of an idle trunk, it will be appreciated that due to inertia, the brush carriage will frequently overjump the desired set of terminals if the trunk becomes 30 idle and the power is cut off while the test brush is traveling over the latter portion of the face of its test terminal. Consideration of the mechanical relation between the test contacts and their associated line contacts 35 appearing in a terminal board of this type will make this clear.

It will be noted that the test brush and its associated line brushes of any set engage the edge of the fixed terminals at substantially 40 the same instant, both the brushes and terminals being vertically aligned. Now assume that the trunk represented by the terminals over which a set of three brushes is traveling becomes idle while the brushes are traversing 45 the latter part of the face of the fixed terminals. The test relay will, of course, respond and cut off the power; too late, however, to prevent the inertia of the brush carriage from causing it to overjump the desired trunk. In accordance with this feature 50 of the invention, I so arrange the apparatus and circuits that the means necessary to arrest the travel of the brush carriage may be actuated only in case a sufficient margin exists to permit the carriage to 55 be arrested on the terminals which initiated the arresting movement. One way of accomplishing this result is to divide the duration of travel of a test brush over a test terminal 60 into two periods, the first of which may be

called the "safe" and the latter the "danger" period, and so arrange the test circuit which controls the movement of the brush carriage that if it is not closed during the safe period, it cannot be closed by any 70 change in the electrical condition of that test terminal during the danger period, that is, while the test brush is engaging its latter part, but instead, the carriage will move on and not be arrested until its test brush contacts with a test terminal whose trunk was rendered idle at least when the test brush travels over the initial part thereof.

For the purpose of illustrating the invention, there are shown in the drawings which 80 accompany this application a single selector and the apparatus associated therewith for governing its operation. It will be understood that in the construction of a large telephone exchange system there would be 85 several such selectors operated successively in the establishing of any one connection. The invention herein described and claimed may be applied to the control of any one of such selectors. The one shown is an "office 90 switch" and is the second of a series in an actual exchange.

In the drawings—Figure 1 shows the circuits and apparatus which are directly associated with a single selector switch mechanism; Fig. 2 shows the circuits of a suitable controlling apparatus connected over trunk wires to the selector, the two figures when placed side by side, No. 2 to the left of No. 1, forming a complete circuit diagram of the 100 selector and its controlling apparatus.

In the form of automatic switch shown on Fig. 1, the switch carriage or movable element is provided with a number of sets of multiple brushes, any particular set of which 105 may be selected for service and the switch carriage then advanced over a series of sets of terminals until the selected brushes are brought into engagement with the terminals of an idle line.

The switch carriage or brush-carrying member is of the rotary type, the frame 21 of which is mounted upon a central standard or shaft 22. At the outer end of the frame a number of sets of contact brushes 115 23, 24, 25 are pivotally mounted upon but insulated from a rod 26, and from each other, in position to sweep over sets of line terminals 27, 28, 29. The brushes have inwardly extending arms 30, bearing against 120 which, one for each brush, are springs 31. Latches 32, one for each set of three brushes, are pivotally mounted upon a rod 33 and arranged to normally hold the brushes from being rocked outwardly into line with the 125 stationary terminals. Bearing against the inner ends of the latches are springs 34 which hold the latches firmly against a stop rod 36. This stop rod 36 serves to prevent the latches from being moved forward too 130

far after the brushes have been released. A stop bar 35 serves to limit the outward movement of the brushes when the latches are withdrawn. The latches 32 and the stop bar 35 are of insulating material so that the circuits connected with the brushes will not be crossed thereby. The springs 31 make electrical connection with the brushes; they are of sheet metal and form the teeth of combs which connect corresponding terminals in the several sets of stationary full-wire clip terminals 27, 28 and 29 and provided for the circuit connections to the springs and brushes.

15 As the brush carriage is rotated to cause the brushes to sweep over the fixed terminals, the latches first pass by a tripping device or brush selector, by which any desired set of brushes may be released and caused to swing outwardly. This tripping device comprises a shaft 40 provided with radially extending fingers 41 arranged spirally about the surface of the shaft. This shaft is adapted by mechanism, to be presently described, to be rotated so as to bring the fingers one after another into the line of travel of the several latches on the brush carriage. Only one set of brushes is intended to be released in a given operation.

20 The shaft is first rotated to bring a particular finger into position to engage the latch in the same level therewith and then the brush carriage is rotated. In passing, the outward edge of this latch strikes the end of the finger, allowing one set of three brushes to be released. Continued movement of the brush carriage brings the selected set of brushes into engagement with the rows of stationary terminals in the same 25 level therewith, these brushes trailing over the terminals and making contact therewith in passing. The brush carriage is finally caused to stop with the selected brushes in contact with some set of stationary terminals. The other brushes, not being released, are held out of contact with the terminals over which they pass. A further movement of the brush carriage in the same direction of rotation will carry the brushes 30 over a restoring roller 63, which may be pivoted to the frame and which engages the free ends of the released set, causing them to be pushed back into their normal latched position. After making a full revolution, 35 the brush carriage is brought to rest in its normal position again.

In the normal position of the brush carriage, the levers 42, 43 pivoted to the rod 36, the latter insulated therefrom, engage at 40 their free ends a normal stop plate 45. At the end of lever 42 is an insulated roller 71 which lies in a recess of plate 46, and at the end of lever 43 is a right angle extension finger 72 which makes electrical contact with said plate 46. A coil spring 54, acting upon 45 the inwardly extending arm 44 of lever 42 and insulated therefrom, serves to press the latter 42 with considerable force against plate 46, thereby holds the brush carriage securely in its normal position. A flat 50 spring 52 engages an inwardly extending arm 45 of the lever 43 and serves to press the latter 43 inwardly, but with less force than that of the coil spring 54. The spring 52 makes electrical contact with lever 55 55 and is secured to but insulated from the shaft 40 of the brush carriage and terminates in a wire clip 53.

55 As the brush carriage is moved to carry the brushes over the stationary terminals, 60 the roller 71 and the extension arm 72 engage the teeth of a cam plate 50. The roller 71 rides over the teeth while the brushes are passing between successive terminals and drops into a notch as any released set of brushes is centrally located in direct contact with a set of terminals. The extension arm 72 lags behind the roller and engages the edge of a tooth just prior to the engagement of the corresponding fixed terminals 65 by the released set of brushes and leaves the teeth when the brushes are half way across the faces of said fixed terminals, engaging the next tooth just prior to the brushes engaging the next set of fixed terminals. The 70 stop bar 35 engages the inwardly extending arm 45 just as it does the arms 30 of the brushes and thus prevents the extension arm 72 of the lever 43 from touching the bottom of the notches between the teeth of plate 50, 75 while permitting said arm 72 to touch and make contact with the top of the teeth. Due to the mechanical relation just described the extension arm 72 will not break contact with a tooth of plate 50 until after the brushes 80 make contact with the stationary terminals and the roller 71 is ready to drop into a notch. The circuit arrangement, as will presently appear, is such that the motive power for driving the brush carriage cannot be cut off until the contact is thus broken between finger 72 and plate 50 and therefore not until the brushes are in position to make good contact with the stationary terminals. The brush selector is also provided 85 with an interrupter or make and break contact device comprising an arm 56 pivoted to the frame at 57 and engaging at its free end a toothed wheel or cam 58 which rotates with the shaft 40. This arm 56 is adapted 90 in the position of the shaft to engage two contacts 59 and 60. These contacts may be springs, the free ends only of which are shown in the drawing. In its normal position, the free end of the arm 56 lies in a 95 notch of the cam 58 which is deep enough to insure an open connection with both contacts 59 and 60. When the shaft is away from its normal position, however, connection is made continuously with contact 59 100

only. The connection with contact 60 is intermittent, this contact being made when the arm 56 is lifted by each tooth of the cam. There are as many teeth on the cam as there are fingers 41 on the spindle 40 and therefore as many as there are sets of brushes.

The motor mechanism for causing rotation of the brush carriage comprises an annular iron friction disk 61 flexibly mounted at the lower end of the spindle 22, an electromagnet 62 which may be fixed in any suitable manner to the frame, and a constantly rotating shaft 63 carrying an iron driving roller 64. The disk 61, roller 64 and that part of the shaft 63 which extends through the center of the electromagnet 62 form the magnetic circuit of the electromagnet 62. When therefore current is passed through the winding of the magnet, the roller 64 attracts the disk 61 and causes the latter to rotate by frictional contact therewith. A holding electromagnet 65 having a pole piece 66 extending upwardly beneath the disk 61 is adapted when current is passed through its winding to engage the disk and hold it from movement. The power shaft 63 is extended as shown in the drawing to carry a flexibly mounted driving disk 70, which is adapted to engage a roller 67 carried by the spindle 40. An electromagnet 68 controls the engagement of disk 70 and roller 67 in the same manner that the electromagnet 62 controls the engagement of disk 61 and roller 64. These devices are in fact electro-magnetic clutches, one to cause movement of the brush carriage and the other to cause movement of the brush selector.

The complete selector switch mechanism is not shown in the drawings, but the elements 40 thereof appear in their proper relation to one another so as to make clear the manner in which the mechanism operates to inter-connect lines. There may be as many sets of brushes and stationary terminals as desired. For example, the switch mechanism may, as a whole, have ten sets of three brushes each and two hundred sets of fixed terminals arranged in ten levels of twenty sets each. For simplicity in the diagram 50 there are shown only two sets of brushes, the eighth and ninth counting from the top down, and six sets of stationary terminals in two levels corresponding to the two sets of brushes shown.

55 Some of the circuits of the selectors are controlled by sequence switches and there is ordinarily one such sequence switch for each selector. In general, the function of the sequence switch is to move from normal position upon the operation of the sender or controller, and to establish in a definite order at successive stages of the operation the various circuits required to bring into service various devices or parts in proper sequence. 60 The sequence switch consists in its elements

of a movable switch operating member, a number of circuit changers actuated in sequence as said member is moved from one position to another, an electromagnet, and motor mechanism operated or controlled by 70 said magnet for advancing said movable member. In each position to which a movable member of the sequence switch is advanced, a circuit or set of circuits is established by which a given operation of the device under control is made possible, and at the same time another circuit is placed in a condition whereby the motor magnet of the sequence switch may be subsequently actuated so that the sequence switch will then be automatically advanced to the next position, until a new set of circuits is established, bringing about a new operation or electrical condition of the device or devices under control, and so on, and finally upon the dis-establishment of a connection, is returned to its normal position ready for service in establishing another connection.

The switch springs of the sequence switch are not shown in their actual arrangement, but are so located as to give the clearest arrangement of circuits. The positions of the rotary element of the sequence switch in which any of its contacts are closed are indicated by the numbers placed adjacent such contacts, each contact being open in all positions except those indicated by the adjacent numbers. The sequence switch has a special contact governing the local or locking circuit of its motor magnet, such as contact 101, this contact being closed while the rotary element of the sequence switch is in transit from one stopping position to the next to insure that it will take the full movement and not stop in intermediate positions. Instead of designating the closed positions of the special contact 101 of the selector sequence switch, the open positions are indicated and are placed on the opposite side of the contact instead of adjacent to it as in the other sequence switch contacts. For convenience in tracing the circuits separate batteries are shown at various points, but it will be understood that these may, and where located in the same exchange would, in practice be one and the same battery.

A suitable arrangement of controlling apparatus for the selector mechanism is shown in Fig. 2. This apparatus comprises a series of counting relays and a series of controlling switches or keys, together with a stepping relay for operating the counting relays in succession to close contacts in circuit with switches or keys, and a cut-off relay adapted when the circuit is closed simultaneously by one of the counting relays and the particular switch or key depressed, to open the controlling circuit and stop the movement of the selector. As shown, there are two series of counting relays. One se-

130

ries, comprising relays 201 to 208 inclusive, are adapted respectively to close contacts 261 to 268 in circuit with the keys 251 to 258 and the cut-off relay 223. The other series 5 of counting relays 211 to 218 inclusive serve the purpose of closing circuits for relays 201 to 208 and are caused to operate in alternate succession with said relays 201 to 208. These two series of relays may be extended 10 in an obvious manner to include any desired number. The stepping relay 224 is arranged to be energized and deenergized intermittently in the movement of the selector, as will be presently explained. Upon the 15 first energization, it closes its front contact which completes a circuit from battery through contact 234, auxiliary counting relay 211 and back contact of counting relay 201, whereupon relay 211 is energized and 20 closes a locking circuit by way of its front contact 229. Relay 211 also closes front contact 230. Then when the stepping relay is deenergized, its armature falls back and closes its back contact, thereby completing a 25 circuit for counting relay 201 by way of battery, contact 232, winding of counting relay 201, back contact of the second auxiliary counting relay 212, and front contact 230 of the first auxiliary relay 211. Relay 201 30 is thereupon energized and it, like relay 211, closes a locking circuit by way of front contact 261. As before stated, however, said contact is also in circuit with the cut-off relay 223 and the first of a series of controlling 35 switches or keys 251, so that if this key had been depressed, the operation of the first counting relay 201 would cause the cut-off relay 223 to open the circuit of the stepping magnet 224. It therefore follows that the 40 number of impulses of current flowing through the winding of the stepping relay 224 before the cut-off relay 223 shall open the circuit of the stepping relay depends upon the particular controlling switch or 45 key which had been depressed.

The stepping relay 224 is included in a loop which may be associated with the trunk line conductors 235 and 236 leading to the selector switch mechanism shown in Fig. 1, 50 suitable switch contacts 237 and 238 being provided for making the connection when it is desired to cause the selector to perform a particular switching operation. The trunk line conductors 235 and 236 may have associated therewith a third conductor 239 including a resistance 240 and a switch contact 241, which contact may also be closed at or about the time the contacts 237 and 238 are closed.

60 The selector mechanism shown in Fig. 1 may or may not be the first switch to be controlled in the operation of connecting subscribers lines and there are indicated in the trunk line conductors 235, 236 and the 65 associated conductor 239 switch contacts 242,

243 and 244 which indicate contacts of another selector that may be interposed in the circuit when the selecting operation which is about to be described takes place.

Referring now to Fig. 1, which shows the apparatus and circuits associated with the selector switch mechanism, it will be noted that the trunk line conductors 235 and 236 are normally, that is, when the sequence switch is in position 1, connected through 70 sequence switch springs 103 bottom and 104 top to form a loop circuit with a line relay 121 and battery; also that the conductor 239 is connected through an office-switch restoring relay 123 and a normal contact 105 of 75 the sequence switch to battery. Contact springs 103 bottom and 104 top of the sequence switch are closed in the first and second positions thereof, while contacts 104 bottom and 103 top thereof are closed from 80 the sixth to the thirteenth positions, inclusive, to extend the circuit of the trunk line to the brushes 23 and 24 of the selector mechanism. The line relay has a back contact and a front contact which are adapted to complete certain local circuits entering into the control of the selector and the sequence switches, as will presently appear. The trunk of restoring relay 123 is adapted when 85 energized to close a locking circuit for its winding by way of its front contact 126 and battery and at the same time to open contact 129 in the motor magnet circuit of the sequence switch. The test circuit terminates 90 in the test brush 25 of the selector switch mechanism. Leading from the sequence switch contact member 92 adapted to be connected to a test relay 133, is a conductor 93 which is connected by way of spring 52 to the contact lever 43 of the switch carriage 95 mechanism. When the selector is in normal position, this switch lever is resting in contact with the normal stop plate 46, but when the brush carriage moves the brushes over the terminals, the finger 72 of lever 43 makes 100 contact intermittently with the teeth of plate 50 which is connected to ground.

It will be noted that a circuit through conductor 93 may be closed in shunt of the motor control or stop relay 131 at front contact 128 of test relay 133 and sequence switch contact 92 top closed in position 3 when the test relay 133 is energized, and may be 115 opened when the finger 72 rides off the corresponding tooth of the cam plate 50. The 120 motor control relay 131 closes at its back contact a circuit for the motor magnet 62 of the selector, this circuit including also sequence switch contact 110; it also closes at its front contact a circuit for the holding magnet 55 of the selector and a circuit for the motor magnet 81 of the sequence switch, the latter circuit including sequence switch spring 111 bottom and sequence switch contact 110. It will be noted that 130

while the sequence switch is in its normal position, the circuit of its motor magnet 81 may be closed by way of the front contact of the line relay 121 and sequence switch contact 112 top; and that in the second position, the circuit may be closed through the back contact of the line relay 121 and sequence switch contact 111 top. In the second position of the sequence switch, a circuit may also be closed for the motor magnet 68 of the brush selector by way of the front contact of the line relay and sequence switch contact 114 bottom. While the sequence switch is in positions 6 to 1 inclusive, a local circuit is closed for this motor magnet 68 of the brush selector by way of sequence switch contact 114 top, and contact 59, this latter contact being closed at all positions of the brush selector except normal.

It will be understood that the primary function of the selector switch shown in Fig. 1 is to interconnect lines for telephonic communication. As before stated, these lines may be trunks forming intermediate connecting links between the subscribers lines. Thus the conductors 235 and 236 may be extended to the left in Fig. 2 through suitable mechanism and conductors to a calling subscriber's line and conductors 140 and 141, which are connected to terminals 27 and 28 of the selector, may be extended to the right in Fig. 1 through suitable mechanism and conductors to a called subscriber's line. Terminal 29 is connected through a resistance 142 to the free pole of the battery. It will be understood that the terminals 27, 28 and 29 of the selector switch may and would ordinarily be connected in multiple to the corresponding terminals of other selectors as shown.

For a clearer understanding of the description, the following table of the positions of the sequence switch 81, controlling the selector, is given:

45	Position 1	Normal.
	"	2---Brush selection.
	"	3---Trunk hunting.
	"	5---Premature return.
50	"	13---Talking.
	"	16---Return of selector.

The operation of the system is as follows: An operator desiring to establish a particular connection by means of the selector switch mechanism will close one of the keys or controlling switches 251 to 258. It may be assumed that the eighth key, 258, is closed. This will result, as will presently appear, in an operation of the selector, whereby the eighth set of brushes 23, 24 and 25 are tripped, and the brushes are moved over the terminals until connection is made with an idle line. Contacts 237, 238 and 241 are first closed, however, to bring

the controlling apparatus into operative relation to the selector. These, and also contacts 232 and 234, may be operated manually, but preferably by a sequence switch mechanism of the same general construction as that associated with the selector. It is merely for the sake of simplicity in the illustrative diagram that such sequence switch mechanism is omitted in Fig. 2. The closing of contact 241 completes a circuit for the restoring relay 123 from ground, resistance 240, conductor 239, selector sequence switch contact 105 to battery. In operating, the restoring relay closes a locking circuit by way of its own front contact 126. It will thus be noted that the restoring relay will remain energized independently of the sequence switch contact 105, but that it is under the control of contact 241 so that whenever contact 241 is opened subsequently the restoring relay will be deenergized. The closing of contacts 237 and 238 brings the stepping relay 224 into circuit with the line relay 121 over the following path: Battery, winding of relay 121, sequence switch spring 103 bottom, conductor 235, contact 242, contact 237, back contact of cut-off relay 223, the winding of stepping relay 224, contact 238, conductor 236, contact 243, and sequence switch spring 104 top, to ground and back to battery. The closing of this circuit causes the energization of line relay 121 and stepping relay 224. Relay 224 closes a circuit for the first auxiliary counting relay 211 by way of battery, contact 234, winding of relay 211, back contact of the first counting relay 201 and front contact of the stepping relay 224 to ground. Relay 211 thereupon becomes locked in a circuit closed by way of its own front contact 229. It furthermore closes front contact 230 which places the first counting relay 201 in a partially completed circuit which may be subsequently made complete when the stepping relay is deenergized and closes its back contact. The energization of line relay 121 causes the advance of the sequence switch from position 1, its normal position, to position 2. That is to say, the motor magnet 81 is brought into circuit by way of sequence switch spring 112 top and the front contact of the line relay, and the sequence switch advances under the control of its special contact 101 to position 2 in which contact 112 top is open.

In position 2, a circuit is closed for the motor magnet 68 of the brush selector by way of sequence switch spring 114 bottom, and the front contact of the line relay, whereupon the shaft 40 is rotated and a series of contacts are made between the arm 56 and contact 60. A circuit is formed upon the making of such contact from battery, line relay 121, sequence switch spring 116 and

contact 60 to ground through the arm 58 and frame of the selector. This circuit forms a shunt of the stepping relay 224 of the controller apparatus. The stepping relay is therefore deenergized intermittently in the advance movement of the brush selector. The first deenergization causes a circuit to be closed for the first counting relay 201 by way of battery, contact 232, the 16 winding or relay 201, back contact of the second auxiliary counting relay 212, front contact 230 of the first auxiliary counting relay 211 and back contact of the stepping relay 224 to ground. After the first closure 15 of the shunt circuit by way of sequence switch contact 116 and contact 66, the shunt is opened and the stepping relay 224 is again energized, whereupon the second auxiliary counting relay 212 is energized. Upon 20 the second closing of the shunt circuit, the second counting relay 202 is energized. Thus the counting relays are successively energized and are locked in local circuits by the alternate energization and deenergization of the stepping relay 224 controlled by the intermittent shunting of the trunk line circuit by way of contact 60 of the brush selector. Upon the energization of 25 counting relay 208 a circuit will be closed by way of the front contact 208 of relay 208, the eighth controlling switch or key 238 and the winding of cut-off relay 223, which at its back contact opens the circuit of the trunk line. This operation of the cut-off 30 relay will occur upon the eighth closure of the shunt circuit by way of contact 66. The line relay 121 remains energized, however, through the shunt path until the shunt is broken by the arm 56 dropping into the 35 eighth notch of the star wheel 58. The eighth finger 41 is at this time pointing inwardly in position to engage a latch 32. The line relay 121 is now deenergized, the two circuits therefore—one by way of the 40 trunk line and the other by way of contact 66—being open. Current is cut off from the brush selector motor magnet 68 at the front contact of the line relay and a circuit is closed for the motor magnet 61 of the sequence switch by way of sequence switch spring 131 top, and the back contact of the line relay 121, whereupon the sequence switch moves 45 from position 2 to 3. In passing from position 2 to 3, contacts 103 bottom, 104 top, 113 bottom and 116 are opened and springs 92 top, 111 bottom, 109 and 110 are closed. The sequence switch is now in position 3 wherein a circuit is completed for the motor magnet 62 of the selector by way of the back contact 50 of the motor control relay 131 and sequence switch contact 110, whereupon the brush carriage of the selector is moved first past the brush selector and then over the rows of terminals. In passing the brush selector, 55 the selected finger 41 thereof trips the corresponding latch 32, allowing a set of brushes 23, 24 and 25 to be swung outwardly on the pivotal rod 26. These brushes therefore will trail over and make contact with the three rows of terminals in the same level. 60 The brush 25 is now connected in a test circuit partially completed through conductor 93, high resistance winding 132 of test relay 133, sequence switch contact 92 top closed in the right or trunk hunting position of the 65 selector sequence switch, conductor 93, contact spring 51, contact arm 45 upon which it fits and bears, contact finger 72 thereof, and a tooth of rack 50, which rack is grounded. Therefore, when the finger 72 contacts 70 with the first tooth of rack 50 and the line connected with terminals 27, 28, 29, corresponding thereto, is busy the potential of test terminal 29 thereof will be insufficient to cause the high resistance winding 132 to 75 energize the test relay 133 and therefore the travel of the switch carriage will continue to the next set and so on as long as the lines connected to those terminals are busy. When, however, the test brush 25 makes contact with the test terminal 29 of a line which is idle, the full potential will exist upon said terminal and current of sufficient strength flows from battery, resistance 142, said test 80 contact, test brush 25 and to ground at 50 85 over the circuit previously traced including the high resistance winding 132, to energize test relay 133 which immediately closes its low resistance locking winding 134 by way of contact 138 in shunt of the high resistance 90 winding 132, and closes at contact 135, a 95 break in the circuit of the motor-control relay 131, this relay being shunted, however, at this time by the low resistance path to ground at 50 through conductor 93. 100

The low resistance winding in addition to serving as a locking winding permits a flow of current through resistance 142 which is sufficient to materially reduce the potential of the test terminals 29 of all the selector 105 switches connected in multiple therewith, so that the line to which connection is being made will be caused instantly to test busy through switches. A moment later the control lever 43 drops into the space between 110 the teeth on the plate 50 thus opening the switch about the motor control relay 131, whereupon this relay is energized, opening 115 at its back contact the circuit of the motor magnet 62 for the brush carriage, and closing at its front contact a circuit for the holding magnet 65 by way of sequence switch contact 110. The brush carriage is 120 therefore stopped suddenly by the magnet 65. The brushes 23, 24, and 25 are now in contact with the terminals 27, 28 and 29 of a non-busy line. The closing of the front 125 contact of the motor control relay 131 also

completes a circuit for the motor magnet 81 of the sequence switch by way of sequence switch spring 111 bottom, said contact and sequence switch contact 110. The sequence switch thereupon moves out of position 3 through position 5 and into position 13, it being under the control of the special switch contact 101 in passing from position 5 to position 13. This is the talking position of the apparatus in which the circuit of the trunk line conductors 235 and 236 is closed to the brushes 23 and 24 by way of sequence switch spring 103 top and sequence switch spring 104 bottom. In position 6 a local circuit for the motor magnet 68 of the brush selector is closed by way of sequence switch spring 114 top, and the brush selector, having no further function to perform with respect to the connection being made, is returned to its normal position. It is caused to stop in its normal position by the opening of this local circuit at contact 59 when the free end of the arm 56 drops into the deep notch in the star wheel 58.

Recurring to that portion of the operation of the selector when its test brush 25 has just reached the edge of a contact 29 representing a busy line. Assume now that during its travel over the face of said terminal, the line associated therewith becomes idle with the resultant increase in potential caused by the removal from the multiple test contact 29 thereof at another selector of the low resistance winding 134 of a relay similar to that of the selector illustrated. It will be evident that since the test circuit leads by a conductor 93 through spring 52, arm 43, finger 72 thereof, and finds ground by way of the teeth on rack 50, that such increase in potential if occurring during the latter half period of the travel of the test brush over the test terminal—that is, during the danger period, will not arrest the movement of the brush carriage, it being borne in mind that during the entire period the finger 72 is traveling over one of the teeth of rack 50 the test brush 25 has traversed, but a portion of the corresponding test terminal 29; that is to say, the timing of the contact period of the finger 72 with any tooth is such that the test circuit can only be closed while the test brush 25 is in the first half or safe period of its contact with any test terminal 29 of a trunk. This arrangement allows the motor control relay 131 plenty of time to become energized and open the motor magnet circuit in time to insure the arresting of the selected set of brushes upon the set of fixed terminals which initiated the arresting movement.

Consider now that point in the operation of the system when the test relay 133 is excited by the test brush 29 engaging an idle trunk, and causing its armature to include in circuit at its front contact 128 the low

resistance winding 134 to reduce the potential to cause this trunk to test busy at its multiple. It is, of course, essential, after the selector has so seized an idle trunk, that the low resistance winding of the test relay remain in circuit with the test battery to maintain reduced potential upon the multiple test terminals, for should this low resistance path be opened, the trunk in use may be seized at one of its multiples by another selector.

As before explained, the trunk hunting occurs while the sequence switch is in position 3. When the armature of the test relay 133 is attracted by the brush 25 engaging the terminals of an idle line, it closes the circuit of the stop relay 131 from battery through resistance 142, test contact 29, brush 25, conductor 94, winding 134, armature and contact 135 of relay 133, stop relay 131, sequence switch spring 109, to ground. The armature of relay 131 in pulling up closes the circuit for the motor magnet 81 of the sequence switch, and if relays 133 and 131 hold up long enough to allow the contact 101 to close, the sequence switch will move out of position 3 to position 5 under the control of its supervisory contact 101. If, however, they do not hold up long enough for the sequence switch to move out of position 3, the hunting will continue as before. By reference to sequence switch spring 92, it will be noted that the circuit of the high resistance or test winding of 133 is open at the top contact of sequence switch spring 92 after the sequence switch has left position 3. If now the armature of the test relay 133 bounds off of its contacts or is retracted, the circuit of relay 131 will be interrupted and its armature falling back will open the circuit for the sequence switch motor magnet 81 and close the circuit for the motor magnet 62 of the switch carriage. In practice, this retraction of the armature of relay 133 will occur, if at all, prior to the sequence switch reaching fifth position. The circuit for the power magnet 62 will now extend from battery through the winding of the power magnet, back contact and armature of relay 131, sequence switch contact 110 to ground. The switch carriage is thus driven forward until the finger 72 reaches the subnormal contact 136 when the circuit will be completed through the stop relay 131 from battery through resistance 130, lower contact and sequence switch spring 95 now closed, finger 72, arms 43, 45, spring 52, wire 93, sequence switch spring 92, and lower contact winding of relay 131, sequence switch contact 109 to ground, thus energizing the stop relay and interrupting the circuit of the switch carriage motor magnet, the switch carriage thus stopping in the subnormal position. The attraction of the armature of

relay 131 again completed the circuit for the sequence switch motor magnet 81 as before, which under the control of its supervisory contact 101 will move to its thirteenth position, and thus the apparatus will remain with the switch carriage in subnormal position and the sequence switch in position thirteen. As this would interrupt the switching operations, the remaining series of impulses which under normal circumstances would serve to return the operator's controller to normal would not be sent. The controller used would display a busy signal or light as long as it is busy, and the continued glow of this signal would denote trouble to the operator.

To restore the apparatus to its normal condition, contacts 241, 237, 238, 232 and 234 may be opened. The opening of contacts 232 and 234 releases the counting relays by opening their local locking circuits. The opening of contacts 237 and 238 disconnects the stepping relay from the trunk line circuit, and this is preferably done before the circuit is used for telephonic communication. The opening of contact 241 releases relay 123, whereupon front contact 126 is opened and back contact 129 closed. The closing of contact 129 completes a circuit for the motor magnet 81 of the sequence switch by way of sequence switch spring 112 bottom. The sequence switch thereupon advances to position 16. In coming into position 14 contact 109 in the circuit of the motor-control relay 131 is opened and said relay is thereupon deenergized, whereupon its back contact closes a gap in the circuit of the motor magnet 62 of the selector, the other gap, contact 110, of which is closed when the sequence switch reaches position 16. It should be noted that the test relay 133 is in circuit with the motor control relay 131 and also becomes deenergized so that the path through the low resistance locking winding 134 is now open at contact 135, and the trunk is rendered accessible to other selectors. The path through the high resistance winding 132 had become opened at sequence switch spring 92 top when the sequence switch passed out of the third position. The switch carriage is moved around under the control of the motor magnet 62 until it reaches its normal position, whereupon contact is made between the finger 72 of lever 43, and the normal stop plate 46, and a circuit is closed for the motor control relay 131 by way of sequence switch spring 109, the winding of relay 131, sequence switch spring 92 bottom, conductor 93, contact lever 43, normal stop plate 46, sequence switch spring 95 top, resistance 130 to battery. The motor control relay 131 is energized in this circuit and opens at its back contact, the circuit of the motor magnet 62. The closing of the front contact of relay 131 completes circuits as before, one to the holding magnet 65 and one to the motor magnet 81 of the sequence switch, the latter circuit being by way of sequence switch spring 111 bottom. The sequence switch thereupon leaves position 16 and returns to the first or normal position. Upon reaching this normal position, sequence switch contacts 103, 104 and 105, 112 top, 114 top are again closed, and all others opened, placing the apparatus in condition for another series of selecting operations.

Should the operator desire, after pressing key 258, to restore the entire apparatus to normal position immediately, she may do so by merely opening sequence switch contact 241. We will now consider the result of opening such contact. First, the trunk relay 123 will be deenergized and its armature 129 in retracting closes a circuit for the sequence switch motor magnet 81 by way of sequence switch spring 112 bottom, whereupon the sequence switch moves from position 2 through position 3 and into position 5. In this position the driving circuit including the motor magnet 62, closed in the third position, continues closed, and said magnet rotates the brush carriage until the finger 72 engages a contact 136 associated with the rack 50. We will refer to contact segment 136 as a subnormal contact and the position of the brush carriage when engaging said contact, its subnormal position, this contact being located near the end of the range of travel of the carriage. In leaving the third position, the test circuit was opened at sequence switch spring 92 top so that it was impossible for the brush carriage to stop between its normal position and the subnormal contact 136. When the finger 72 contacts with this subnormal contact, however, a circuit is closed for the relay 131 from battery, resistance 130, sequence switch spring 95 bottom closed in position 5, subnormal contact 136, lever 43, spring 52, conductor 93, sequence switch spring 92 bottom, the motor control relay, contact 109 to ground. The motor control relay at its back contact thereupon opens the driving circuit of the selector and at its front contact moves the sequence switch to position 13 by way of contacts 110 and 111 bottom in which position the sequence switch motor magnet is continued energized by way of sequence switch spring 112 bottom and back contact of relay 123 which is now inert, and thereupon the sequence switch moves to position 16, in which position the driving circuit of the selector is again closed at sequence switch contact 110, it being noted that the circuit of motor control relay 131 was opened when the sequence switch left its fifth position. The switch carriage is then rotated to normal, and when the finger 72 engages

segment 46, the circuit previously traced is closed for relay 131 which opens at its back contact the driving circuit and at its front contact moves the sequence switch to normal position. The apparatus is now restored.

Attention is now particularly directed to the provision of an arrangement whereby in case the wipe-out key represented by sequence switch contact 241 is actuated before 10 an idle trunk has been seized the testing circuit is opened to prevent useless subsequent operation; that is, to save time. It will be noted that the test circuit leads through a sequence switch spring 92 top, closed only 15 in the third or testing position. Assume now it is desired to disestablish the connection after having depressed the starting key. It will be remembered that upon the closure of contacts 237, 238 the line relay 121 be- 20 came energized and at its front contact and sequence switch 112 top moved the selector sequence switch to position 2. The office switch restoring relay 123 is rendered inert by the operation of the key 241, with the re- 25 sult that the sequence switch moves to position 3. It will be observed now that the sequence switch contact through which circuit was closed to move the sequence switch to this position remains closed in this posi- 30 tion and enables the sequence switch to move to position 5. In position 3 the driving circuit was closed as before to rotate the brush carriage, but since the sequence switch did not stop in position 3, but moved immedi- 35 ately to position 5, the testing circuit is open at sequence switch spring 92 top, thus preventing the seizing of a trunk, and the brush carriage continues rotating until the arm 45 reaches the subnormal contact from which 40 point the restoring operation is the same as hereinbefore recited.

If, for any reason, upon the operation of the wipe-out key the brush carriage should be given a slight movement, in accordance 45 with the improvement about to be recited, it cannot remain in such displaced relation as will now be more particularly described. It will be appreciated that should the sequence switch and other apparatus be re- 50 stored, except the selector, and notice given the operator that the equipment is ready for another call, upon the next seizure of this particular switch, and the rotation of its spindle to select the desired set of brushes, 55 the brush carriage not being as usual in its normal position, but in close proximity to the spindle, the spindle, when rotated during the brush selecting period, will cause its teeth to trip a number of sets of brushes de- 60 pending, of course, upon the particular set of brushes desired for that connection, and in the next or trunk hunting period these brushes will, instead of being retracted, en- gage the line terminals in this movement,

causing as stated, interference with calls of 65 which multiples of these terminals form a part. This cannot occur with the present system since by the present arrangement it is impossible for the sequence switch to move from normal position through its successive 70 periods and restore without a corresponding restorative movement of the brush carriage; that is to say, a sort of interlocking arrangement is provided in which the sequence switch having been once moved out of its 75 normal position, must cause a complete revolution of the brush carriage before it can be restored to normal position. It will be noted that a selector in being restored after having been used in establishing a suc- 80 cessful call does not stop at this subnormal contact, since the sequence switch is then in position 16 when contact 95 bottom is open.

I claim:

1. The combination with a selector, of a 85 test brush and fixed terminals adapted to be traversed thereby, means for initially moving said selector and means governed by the electrical condition of any one of said terminals during a portion of the period the 90 test brush is in contact therewith for controlling the continued movement of said selector.

2. In the combination with a selector hav- 95 ing test terminals, a test brush and means for causing said brush to traverse said terminals, and a test circuit for arresting said brush upon an idle terminal, said test circuit being interrupted during a portion of the period the test brush is traversing any 100 test terminal.

3. The combination with a selector, where- 105 in the trunks are represented by fixed terminals whose electrical condition determines their idle or busy condition, the said fixed test terminals, a test brush therefor, power- driven means for moving said brush, of means for arresting its movement when en- gaging an idle trunk, and means for pre- 110 venting said arresting means from becoming operative due to a change in the electrical condition of a test terminal while said brush is engaging the latter portion thereof.

4. In combination with a selector, the 115 continuation of whose advance is determined by the electrical condition of the fixed terminals which its test brush engages, the said fixed test terminals and the test brush, of a power-shaft, a magnetic clutch for coupling said power-shaft to said brush, and 120 a relay responsive to the electrical condition of the first portion only of any test terminal for uncoupling said clutch.

5. In combination with a power-driven 125 trunk hunting switch having a test relay for controlling the seizure of idle trunks by its responsiveness to the electrical condition of their test terminals, and a test brush, with

- means for driving said brush, said test relay being connected to said brush and adapted to operate to cause the disconnection of said driving means from said brush, and a switching device adapted to close an operative circuit for said test relay only when the test brush is engaging the first part of a fixed terminal representing an idle trunk.
16. In a telephone exchange system, the combination with a selector, a switching device controlling its operation and having a normal position and a number of abnormal positions, a sender for initiating and normally governing the operation of said switching device, and thereby said selector, means at the sender for prematurely disestablishing a partially completed connection, and means actuated thereby for causing said switching device to move through its abnormal positions and return to its normal position, and cause a complete operation of said selector.
17. In a telephone exchange system, the combination with a selector, a sequence switch controlling its operation, a sender governing the operation of the sequence switch, means actuated by the sender in initiating a call for moving the sequence switch out of its normal position, premature disconnecting means for causing immediate restoration of said sequence switch without establishing a telephonic communication, and means actuated by the sequence switch during its restoration to cause a complete operation of said selector.
18. In a telephone exchange system, the combination with a selector, a sequence switch controlling the same, a sender controlling the selector and sequence switch, means at the sender for causing the sequence switch to move out of its normal position, means controlled by the operator for causing continued movement of said sequence switch, and means controlled by said sequence switch in its movement for advancing said selector, and circuits closed by said selector and sequence switch alternately for permitting each other restoration to normal position.
19. In a telephone exchange system, the combination with a selector, a sequence switch controlling the same, a sender governing the operation of said sequence switch and thereby said selector, a restoring relay, a line relay, circuits therefor closed upon the initiation of a call, the energization of said line relay causing the said sequence switch to move out of its normal position, a key at the sender for opening the circuit of said restoring relay to prematurely disestablish a partially completed connection, the deenergization of said restoring relay closing a circuit to advance said sequence switch, and circuits alternately closed by said sequence
- switch and selector for restoring each other to normal position.
20. The combination with a selector having test terminals, a test brush, means for advancing and restoring said brush, a test circuit associated with said brush including a path of high resistance closed when said brush is testing, and a path of low resistance closed when said brush has come to rest upon a terminal, and means actuated upon the subsequent opening of said low resistance path for causing the restoration of said selector.
21. The combination with a selector having test terminals, a sequence switch controlling its operation, a test brush, means for moving and restoring the same, a test circuit associated with said brush including a path of high resistance closed when said brush is testing and a path of low resistance closed when said brush has come to rest upon a terminal, and means actuated upon the subsequent opening of said low resistance path for causing the restoration of said selector and sequence switch.
22. The combination with a trunk-hunting selector having a group of trunks represented by fixed test contacts, of a circuit for testing said trunks, a sequence switch for controlling said selector, a sender controlling said sequence switch, means controlled by said sender for initiating the operation of said sequence switch and thereby said trunk-hunting selector, and means associated with the sender for preventing said switch from testing said trunks in its movement, and for restoring the said selector and sequence switch to normal position.
23. The combination with a trunk-hunting selector having a group of trunks represented by fixed test terminals, of a circuit for testing said trunks, a sequence switch for controlling said selector, a sender for initiating movement of said sequence switch and thereby said selector, and a wipe-out key associated with the sender and means controlled by the wipe-out key for causing said sequence switch to move through the testing position without stopping and thus prevent the selector from seizing an idle trunk.
24. The combination with a selector having test terminals, and test brush and means for advancing and restoring said brush, of means governed by the electrical condition of the idle test terminals for arresting the movement of said brush, means actuated upon the seizure of an idle trunk for changing the electrical condition of its test terminal, and means rendered active upon the regaining of the original electrical condition for causing the immediate actuation of said selector restoring means.
25. The combination with a selector having a test brush, a row of test terminals and line brushes and rows of line terminals,

means for initially moving said brushes over said terminals, means governed by the electrical condition of said test terminals for arresting their travel, said means being
6 adapted to be actuated only during the period the said line brushes are engaging the first part of said line terminals.

In witness whereof, I hereunto subscribe my name this 19th day of March A. D., 1912.

FRANK N. REEVES.
